(57) **CLAIM**

I claim the ornamental design for the locket, as shown and described.

DESCRIPTION

FIG. 1 is a front perspective of the locket showing my new design in an open position;

FIG. 2 is a right side elevational view thereof in closed position;

FIG. 3 is a left side elevational view shown in closed position;

FIG. 4 is a front elevational view shown in open position;

FIG. 5 is a front elevational view shown in closed position;

FIG. 6 is a rear elevational view, the broken lines showing the wristlet or bracelet which goes through the two attachment means affixed to the back of the locket;

FIG. 7 is a top plan view of the locket shown in closed position; and,

FIG. 8 is a bottom plan view of the locket shown in closed position.

It being understood that the broken lines are for exemplary illustrative purposes only and form no part of the claimed design.
